UNITED STATES PATENT OFFICE.

JOSEPH A. STEINMETZ, OF PHILADELPHIA, PENNSYLVANIA.

MEANS FOR DESTROYING AIR-CRAFT.

1,092,760.

Specification of Letters Patent. Patented Apr. 7, 1914.

Application filed May 19, 1913. Serial No. 768,515.

To all whom it may concern:

Be it known that I, JOSEPH A. STEINMETZ, a citizen of the United States, residing at Philadelphia, in the county of Philadelphia and State of Pennsylvania, have invented certain new and useful Improvements in Means for Destroying Air-Craft, of which the following is a specification, reference being had therein to the accompanying drawing.

This invention relates to offensive operations against air craft and its object is to provide for the destruction of an air ship by another air ship which itself incurs little risk or injury. Preferably, the attacking air ship is an aeroplane, since this type of airship is capable of quickly changing its direction at high speed and of rising or falling at the will of the operator.

The invention involves lowering bombs to a suitable distance from air craft in flight, by means of a wire or other flexible connection, and providing the upper side or end of each bomb with contact devices adapted to cause an explosion when the bomb is drawn upwardly by deflection of its supporting wire through its meeting an airship. Such deflection must occur whenever there is contact between the laterally moving, pendant wire and an airship, except only in the highly improbable case where the wire and the attacked airship are moving in the same direction at substantially the same speed, when explosion can be caused by manually pulling the wire.

In the accompanying drawings, Figure 1 is a diagrammatic representation of an aeroplane provided with my devices and attacking an airship far below. Fig. 2 represents a reel carried by the attacking craft and supporting the bomb at some distance below the craft attacked.

In these figures, A represents an aeroplane provided with a reel B from which a bomb C is suspended by a flexible connection D, which may be piano wire, and E an airship, shown in this instance as a dirigible balloon in a plane between the planes of the aeroplane and bomb. Deflection of the wire by the airship, whether from its own motion or that of the wire, or both, causes slipping of the wire at the point of contact and brings the bomb quickly against airship, and the bomb being provided above with a suitable contact device, then explodes. It is preferably charged with a high explosive in quan-

tity sufficient to insure disaster to the airship without injury to the aeroplane which is far above. The reel is controlled by the aviator on the aeroplane and may be of any suitable known type, such, if desired, as to secure very rapid winding and unwinding, and the bomb has its lower part the heavier so that in falling freely the contact device may be uppermost and thus not receive the shock of direct impact when the bomb strikes the earth.

In attack, the bomb-carrying machine ascends to a considerable distance above the plane of the attacked craft and lowers its bomb to a point below that plane, the distance below not being very material, and then moves in such path as to cause lateral contact of the wire and the attacked object. The aeroplane, or any number of them, may move at such distance apart or in such paths that neither endangers the other, and obviously no large and comparatively slow turning craft could long escape disastrous contact with one of the wires, while smaller craft of any type would find it extremely difficult to avoid destruction. The devices may be employed by night or day, although in daylight the wire is not usually visible at any considerable distance and the bomb itself which may be small, weighing but a few pounds, is not readily detected by the eye. For attack, aeroplanes have very decided advantages in that their evolutions may be rapid and their speed in any direction may be high whatever the direction of ordinary air currents. A fleet of such craft may effectually defend a city, for example, and may also make the conveyance and landing of any considerable hostile force out of the question.

The reel should carry a surplus of wire and a reserve supply of bombs should be at hand so that in case it is desired another bomb may quickly replace one exploded or lost, and obviously the ordinary contact device may be replaced by other means for securing explosion at the proper instant.

If desired, the reel may be operated at high speed by using the motive power of the engine which drives the aeroplane.

What I claim is:

1. For destroying air-craft when the destroyer is in free flight, the combination with a flying machine, of a bomb far below said machine, suspended freely therefrom by a readily flexed connection, and provided with

a contact device in position to cause explosion of the bomb when the latter is drawn vertically upward against the said air-craft which deflects that portion of the connection 5 between said machine and bomb by relative lateral movement of the connection and air-craft.

2. The combination with an aeroplane provided with a suitable reel controllable by 10 the aviator, of a flexible wire or the like depending from said reel, and a bomb provided

on its uppermost side with a contact device secured to the lower end of the wire, to be drawn upwardly into contact with any body causing lateral deflection of the wire between 15 the bomb and reel.

In testimony whereof I affix my signature in presence of two witnesses.

JOSEPH A. STEINMETZ.
